(57) **CLAIM**

The ornamental design for a resonance chamber disposed about a conduit contour of an emission system, as shown and described.

DESCRIPTION

FIG. 1 is a perspective view of a resonance chamber of an embodiment of the present invention;

FIG. 2 is a front side elevation view thereof;

FIG. 3 is a back side elevational view thereof;

FIG. 4 is a top plan view thereof, a bottom plan view thereof being a mirror image thereof; and,

FIG. 5 is a right side elevational view thereof.

The broken lines shown in the drawings are directed toward environment, are for informational purposes only, and form no part of the claimed design. The boundary lines of the conduit are shown in evenly spaced, dashed lines and are not intended to form part of the claimed design.
